UNITED STATES PATENT OFFICE.

CHARLES W. SLEEPER, OF LANCASTER, NEW HAMPSHIRE, ASSIGNOR TO
THE SLEEPER MACHINE COMPANY, OF MAINE.

CAN BEADING AND FLANGING MACHINE.

SPECIFICATION forming part of Letters Patent No. 665,478, dated January 8, 1901.

Application filed October 5, 1900. Serial No. 32,075. (No model.)

To all whom it may concern:

Be it known that I, CHARLES W. SLEEPER, a subject of the Queen of Great Britain and Ireland, residing at Lancaster, in the county 5 of Coos and State of New Hampshire, have invented a new and useful Improvement in Can Beading and Flanging Machines, of which the following is a specification.

"Beading" is the process of forming a 10 raised ridge around the body of the can either on the inside or the outside of the can-body, the object of the bead being to stiffen the body of the can or form a stop for a head or cover, or both.

"Flanging" is the process of turning a portion of the end of the can-body either inward or outward to form an angle with the surface of the cylinder.

These operations have usually been performed on separate machines, on which the cans have been placed by hand and the pressure of the rolls applied and regulated by means of a foot-treadle.

The purpose of my invention is the production of a machine adapted to perform both 25 said operations at the same time or either of them separately and in which the said operations, including the regulation of the pressure of the beading and flanging rolls, are performed automatically.

In the drawings accompanying this specification, Figure 1 is a front view of my invention with portions of the column removed to show details of construction. Fig. 2 is a 35 side view of the same with a portion of the column cut away and showing but one beading device. Fig. 3 is a top view of my machine with two beading devices shown. Figs. 4 and 5 are details of beading device. Figs. 40 6 and 7 are details of parts for moving and latching the head. Fig. 8 is a detail showing the beading and flanging rolls. Fig. 9 is a detail showing the mechanism for regulating the distance between the beading or 45 flanging rolls. Fig. 10 is a detail giving side view of flanged disk c^7 .

A is the base of the machine, and B the supporting-column, in the upper part of which is journaled a hollow shaft or sleeve e^8 , upon 50 one end of which the head c^8 for carrying the beading or flanging devices is loosely mount-

ed in such manner as to be capable of rotation on said shaft.

c^7 is a flanged disk connected with the head c^8 by the barrel c^9 . The rim of the disk c^7 is 55 cut through by four rectangular slots 1 2 3 4.

e^7 is a segment-gear keyed to the sleeve e^8 and having its face parallel to that of the disk c^7 .

c is a shaft passing through the column B. 60 c' is a cam on said shaft.

c^2 is a cam-rod engaged by the cam c' and attached to a latch-bolt c^3 , guided between lugs c^4 , projecting inside the column B.

c^5 is a latch-bolt carried between projecting lugs on the face of the segment-gear e^7 65 and resting against the coiled spring c^6 . This bolt projects over the rim of the disk c^7 and within its periphery and is adapted to engage the slots in said rim at the proper stages 70 in the operation of the machine.

e is a shaft driven by a pulley e' and carrying a pinion e^2 , which engages a gear e^3 on the shaft c . The gear e^3 is provided with a crank-pin e^{10} and is connected by a rod e^4 to 75 a pin e^{11} upon the sliding rack e^5 , which is guided in suitable ways in the side of the column B and held in place by a cap e^6 .

The reciprocating motion imparted to the rack e^5 by the revolutions of the gear e^3 causes 80 the segment-gear e^7 , engaged by the rack, to oscillate through an arc of ninety degrees. When the rack e^5 is at its lowest position, as in Fig. 6, the slot 1 in the rim of the disk c^7 is engaged by the latch-bolt c^5 and is in line 85 with the bolt c^3 . At this point the bolt c^3 rises and entering the slot 1 pushes the latch-bolt c^5 upward until it leaves the slot, and upon the return motion of the segment-gear the latch-bolt c^5 bears against the inner surface of the rim of the disk c^7 , as shown by dotted lines, Fig. 7, and on reaching slot 2 is forced into the same by the spring c^6 , thereby locking the segment-gear e^7 to the disk c^7 . At the same instant the bolt c^3 is withdrawn 90 from slot 1, and as the rack e^5 descends the disk c^7 and revolving head c^8 are moved through an arc of ninety degrees, when the bolt c^3 enters the slot 2 and holds the head in position while the bolt c^5 returns to engage 95 slot 3. As the motion of gear e^3 is continuous the head c^8 is given an intermittent mo-

tion with an advance of ninety degrees and with its period of motion equal to its period of rest.

A shaft f passes through the sleeve e^8 and is provided with bevel-gears f' f^5 upon each end. The gear f' is engaged by a gear f^2 upon a shaft f^3 , which is driven by a pulley f^4 .

The beading or flanging devices, of which there are four, are secured to the face of the head c^8 , as in Fig. 1, and described as follows:

Referring to Figs. 4, 5, and 8, c^{10} is a journal-box secured to the head c^8 and provided with ears d^7 . c^{11} is a swinging frame pivoted upon the pin d^8 , which passes through the ears d^7 . Screws d^9 engage the pins d^8 and serve to adjust the position of the frame c^{11} , the hole through the frame at this point being oblong to permit of vertical adjustment upon the pin d^8 . The frame c^{11} is bored 80 through in a line parallel with c^{10} and carries a spindle d . A similar spindle d' is carried by the box c^{10} . The spindles d d' are connected by gears c^{12} c^{13} , and a gear c^{14} upon the spindle d' is driven by the gear f^5 upon the shaft f , giving continuous motion to the spindles d d' . The spindles d d' are designed to carry beading-rolls d^2 d^3 or flanging-rolls d^4 d^5 , or both. Fig. 8 shows the parts arranged for beading one end of the can and flanging 95 the other end. The rolls are held upon the spindles by nuts d^6 , suitable collars d^{11} being provided to set the rolls in proper relation to each other. A bracket d^{12} carries a plate d^{13} , to which is secured a shell d^{10} , for supporting 100 the can-body, of a diameter one-quarter of an inch smaller than the can-body. The bracket d^{12} is slotted to provide for adjustment of the position of plate d^{13} . The upper portion of the shell d^{10} is cut away in a longitudinal slot 105 sufficiently to prevent interference with the action of the rolls. A sliding bar c^{15} , carrying a rack c^{16} , engaging with gear-teeth upon the swinging frame c^{11} , is guided by a suitable groove in the under side of the journal-box c^{10} and is provided with a pin and roller c^{20} to engage the cam-groove c^{17} in a sliding bar c^{18} , which is guided in a suitable groove cut into the face of the head c^8 . The bar c^{18} is provided with a pin and roller c^{21} to engage 110 the groove of a cam c^{19} , which is secured to the sleeve e^8 and oscillates with it.

It will be understood that as the head c^8 revolves the bars c^{18} are given reciprocating motion by the cam c^{19} and impart similar motion 115 to the rack-carrying slide c^{15} , and as the rack c^{16} engages the gear-teeth upon the swinging frame c^{11} the spindle d and its beading or flanging rolls are made to approach and recede from the spindle d' as the head revolves.

In operation the can-body is placed, either by hand or automatically by a forming-machine, upon the shell d^{10} of the beading device at the left side of the machine, as shown in Fig. 1, the rolls being held apart at this point by the 120 cam c^{19} . The first motion of the head brings the beading device, carrying the can-body, to its upper vertical position, where the can-body

drops by gravity to the plate d^{13} . When the head c^8 has remained at this position about one-half of its period of rest, the cam c^{19} in 70 its oscillation causes the beading-rolls to grasp the can-body and gradually press it between the rolls while they revolve. The second motion of the head brings the beading device, with its can-body, to a horizontal position at the right side of the machine. During its period of motion the can is revolved between the rolls without any increase in pressure; but as soon as the head is at rest the cam again 75 presses the rolls together and increases the pressure gradually during the period of rest. The third motion of the head brings the beading device to its lower vertical position, and during about one half of its period of rest the rolls continue their pressure upon the can-body and are then moved apart by the cam c^{19} , and the can-body falls from the machine by gravity. The fourth motion of the head 80 brings it to its first position.

What I claim, and desire to secure by Letters Patent, is—

1. In a machine of the class specified the revoluble head c^8 with a plurality of beading or flanging devices mounted radially thereon, each consisting of a pair of spindles carrying 95 suitable beading or flanging rolls and connected by suitable gears, means for giving said head intermittent rotary motion, means for rotating said spindles and means for regulating the pressure of said rolls upon the cans operated upon substantially as described.

2. In a machine of the class specified the revoluble head c^8 with the flanged disk c^7 connected therewith having slots 1, 2, 3, 4 in its 105 rim, segment-gear e^7 operated by rack e^5 , means for giving said rack e^5 reciprocating motion, means for alternately locking said segment-gear to said disk c^7 and unlocking the same, and means for locking said disk c^7 110 during the backward movement of the segment-gear, substantially as described.

3. In a machine of the class specified the revoluble head c^8 with the flanged disk c^7 connected therewith having slots 1, 2, 3, 4 in its 115 rim, segment-gear e^7 operated by the rack e^5 , latch-bolt c^5 and spring c^6 mounted on said segment-gear, latch-bolt c^3 mounted on the frame of the machine, means for operating said rack e^5 and means for operating said 120 latch-bolt c^3 , substantially as described.

4. In a machine of the class specified the revoluble head c^8 with the flanged disk c^7 connected therewith having slots 1, 2, 3, 4 in its 125 rim, segment-gear e^7 operated by the rack e^5 , latch-bolt c^5 mounted on said segment-gear, latch-bolt c^3 operated by the cam c and cam-rod c^2 , means for operating said cam c and means for giving to said rack e^5 reciprocating motion substantially as described.

5. In a machine of the class specified the swinging frame c^{11} carrying roll-bearing spindle d , in combination with the stationary frame c^{10} carrying roll-bearing spindle d'

means for rotating said spindles and means for giving oscillating motion to said frame c^{11} substantially as described.

6. In a machine of the class specified the 5 revoluble head c^8 having a plurality of sets of roll-bearing spindles d d' mounted radially thereon, means for rotating said spindles and means for bringing the rolls in each set into varying distances from each other substantially as described.

7. In a machine of the class specified a plurality of sets of roll-bearing spindles d d' mounted radially upon a revoluble head c^8 , the inner ends of said spindles being connected by gears c^{12} c^{13} , in combination with bevel-gears c^{14} on the spindles d' , and the central bevel-gear f^5 mounted on the shaft f , means for rotating said shaft and means for bringing the rolls into varying distances from each 20 other, substantially as described.

8. In a machine of the class specified the roll-bearing spindles d' journaled in the frame c^{10} on the face of the revoluble head c^8 , swinging frames c^{11} with roll-bearing spindles d journaled therein, gears c^{12} c^{13} connecting said spindles d d' , means for rotating said spindles, means for giving to said head c^8 intermittent rotary motion and means for varying the pressure of said rolls upon the can to be 30 operated upon substantially as described.

9. In a machine of the class specified the roll-bearing spindles d' journaled in the frame c^{10} on the face of the revoluble head c^8 , swinging frames c^{11} with roll-bearing spindles d 35 journaled therein, sliding bars c^{15} with racks c^{16} , sliding in grooves in frames c^{10} and en-

gaging gear-teeth on the frames c^{11} and means for giving to said sliding bars c^{15} reciprocating motion substantially as described.

10. In a machine of the class specified the 40 roll-bearing spindles d' journaled in the frame c^{10} on the face of the revoluble head c^8 , swinging frame c^{11} with roll-bearing spindles d journaled therein, sliding bars c^{15} with rack c^{16} carried by the frame c^{10} and engaging gear-teeth on the frame c^{11} , pin and roller c^{20} on said sliding bar, engaging the groove c^{17} in the sliding bar c^{18} mounted on said head c^8 , and means for giving said sliding bar c^{18} intermittent reciprocating motion substantially 50 as described.

11. In a machine of the class specified the roll-bearing spindles d' journaled in the frames c^{10} on the face of the revoluble head c^8 , swinging frames c^{11} with roll-bearing spindles d journaled therein, sliding bars c^{15} with rack c^{16} carried by the frames c^{10} and engaging gear-teeth on the frame c^{11} pins and rollers c^{20} on said sliding bars engaging grooves c^{17} in sliding bars c^{18} on said head c^8 , cam c^{19} secured to oscillating sleeve e^8 , and having a cam-groove in its face engaging pins and rollers c^{21} on said bars c^{18} , and means for giving oscillating motion to the sleeve e^8 substantially as described. 65

In testimony whereof I have signed my name to this specification in the presence of two subscribing witnesses.

CHARLES W. SLEEPER.
